SLIDE-VALVE

Application filed February

My invention relates to a slide valve mechanism for internal combustion engines of the four cycle type.

One of the objects of my invention is to provide a plug and sleeve valve mechanism in which the sleeve will admit the gaseous mixture freely into the combustion chamber during the suction stroke of the main piston and for a part of its return stroke, and in which 10 the plug will quickly cut off the inlet at a predetermined point during the beginning of said return stroke.

In my prior Patent No. 1,492,573, of May 6 1924, the ported sleeve valve of itself opened 15 kept open and closed the inlet port. I have ascertained that with such a construction the closing of the inlet by the sleeve began too soon and that a long time was occupied in the closing action. The amount of gaseous mixture fed in was thereby reduced.

In accordance with my invention, I utilize the ported sleeve valve to open and keep open the inlet and cause the plug in the admission period of the gaseous mixture to quickly close 25 the inlet and stop the admission. The amount of the gaseous mixture fed into the combustion chamber is thereby increased. The plug after the admission is stopped, is caused to block the inlet during the compression and 30 firing cycles, thus preventing the gaseous mixture from being forced back through the port in the sleeve.

With the above and other objects in view my invention consists in the parts, improvements and combinations more fully pointed out hereinafter.

Turning now to the drawings:

Figure 1, is a sectional detail of the plug and sleeve valve mechanism, in which the sleeve is about to open the inlet passage in the valve head.

Figure 2, is a sectional detail, showing the sleeve keeping the inlet passage open.

Figure 3, is a sectional detail showing the plug closing the inlet.

Figure 4, is a longitudinal section through the cylinder of the engine, with the plug closing the inlet and with the working piston at the beginning of the return stroke.

Figure 5, is a diagram showing the rela-

haft.

e mechanism is arranged in the
he cylinder. This consists of a
3 and a plug valve 17, the sleeve 75
ated by connecting rod 18, and
verhead valve shaft 15, and the
ciprocated within the sleeve by
d 20 and crank 21, connected

d valve shaft 15, and separated 80
from crank 19. The sleeve is
a prolonged port 22, and the
e sleeve port to the inlet pas-
h that the sleeve port, itself,
et passage 8, by its movement 85
passage. At this time the crank,

es the sleeve is at the inlet posi-
shown as approximately sixty
ts top dead center. At this time
arranged as not to block the 90
operating crank being at about

itter when the crank of the main
t five degrees past its top dead
commencement of the opening of
hown in Figure 1. The sleeve 95
e intake fully open. The intake
lly open in Figure 2. During
vations the port 22 in the sleeve

the inlet passage 8, and the
fect in determining the admis- 100

the inlet passage 8, and the
fect in determining the admis-

sion in either of these operations. Between the positions of the parts shown in Figure 2, and in Figure 3, the plug begins to close the inlet. The port 22 in the sleeve continues to register with the inlet passage 8.

When the valve parts are moving from the position shown in Figure 1, toward the position shown in Figure 2, the main piston 1 has accomplished its suction stroke, and has begun its return. During the beginning of this return the main piston arrives at the position shown in Figure 4. The plug valve, which as shown in Figures 2 and 3, by reason of the position of its operating crank 21, is moving rapidly downward and when crank 4, of the main piston has made about a quarter turn past bottom dead center, as shown in Figure 4, the plug closes the port in the sleeve, cutting off the admission. The plug, after the admission is stopped, blocks the inlet during the compression and firing cycles and thus prevents the gaseous mixture from being forced back through the port in the sleeve.

In the best embodiment of the invention, the port in the sleeve by reason of its wide, horizontal cross-sectional area with relation to the cross-sectional areas of the inlet, does not throttle the admission of the gaseous mixture. The closing of the admission and the reduction in area of the admission passage to the combustion chamber, is controlled by the plug. This is shown in Figure 5, in which the admission begins at point A (the parts being then in the position shown in Figure 1), the sleeve continues to open the admission until the point B is reached. The sleeve port now keeps the inlet full open from the point B to the point C (the parts at a point along the line B—C have assumed the position shown in Figure 2). From the position C to the position D, the plug is throttling and closing the inlet, D indicating the closure (with the parts in the position shown in Figures 3 and 4).

Having thus described the construction and operation of the invention, it will be understood that changes may be made in carrying the invention into effect without departing from the principle thereof.

What I claim is:

1. In an internal combustion engine of the four cycle type comprising a working cylinder, a valve head, forming an axial extension of the cylinder, provided with an inlet passage and an exhaust passage, and having a working piston within said cylinder, a sleeve slide valve reciprocating within said valve head, a plug within said slide valve, said sleeve valve provided with a port and with a skirt portion for controlling the exhaust passage, and means whereby a pair of separated cranks reciprocate said sleeve and plug, so that the port in the sleeve, by its movement with relation to the inlet passage

in the cylinder, in itself, opens and keeps open the inlet for the admission of gas during the inlet cycle and the plug will cut off the admission of gas, at the beginning of the return stroke of the working piston, said plug with the inlet cut off blocking the inlet port during the compression and firing cycles.

2. In an internal combustion engine of the four cycle type comprising a cylinder, a working piston reciprocating in said cylinder, and a valve head forming an axial extension of said cylinder, the valve head being provided with an outer inlet passage and an inner exhaust passage, a sleeve slide valve reciprocating within said head, a plug within said slide valve, said sleeve valve provided with an inlet port and with a skirt portion controlling the exhaust passage, an overhead half-speed valve shaft, means whereby a pair of cranks and connecting rod connections between said valve shaft and said sleeve and plug valves respectively, reciprocate said valves, whereby said inlet passage is opened and kept open by the inlet port in the sleeve and the plug is actuated to cut off the admission at about one quarter of the return stroke of the working piston and to block the inlet port during the compression and firing cycles.

3. In an internal combustion engine of the four cycle type comprising a working cylinder, a working piston reciprocating within said cylinder, and a valve head forming an axial extension of said cylinder, provided with an inlet passage and an exhaust passage, a sleeve slide valve reciprocating within said valve head, a plug within said slide valve, said sleeve valve provided with a skirt portion controlling the exhaust passage and with a non-throttling inlet port, the cross-sectional area of the inlet port being greater than the cross-sectional area of the inlet passage, and means whereby a pair of cranks reciprocate said sleeve and plug, so that the inlet port in the sleeve in itself, opens and keeps open the inlet for the admission of gas during the inlet cycle, and the plug will cut off the admission of gas at the beginning of the return stroke of the working piston, said plug with the inlet cut off blocking the inlet port during the compression and firing cycles.

4. In an internal combustion engine of the four cycle type comprising a working cylinder, a valve head provided with an exhaust and an inlet passage, a ported sleeve valve and a plug valve within said valve head, the combination of means for reciprocating said sleeve valve to open and keep open the inlet and means for reciprocating the plug valve to cut off the inlet.

In testimony whereof, I have signed my name to this specification.
